US00D922079S

(12) **United States Design Patent** (10) **Patent No.:** **US D922,079 S**
Breeden, III et al. (45) **Date of Patent:** **** Jun. 15, 2021**

(54) **SHEET WITH CAMOUFLAGE PATTERN**

- (71) Applicant: **WINSTON PRODUCTS, LLC**,
Cleveland, OH (US)
- (72) Inventors: **Winston H. Breeden, III**, Chagrin
Falls, OH (US); **Ryan W. Chepla**,
Orange Village, OH (US); **Christine L.**
Gurgul, Sagamore Hills, OH (US)
- (73) Assignee: **WINSTON PRODUCTS LLC**,
Cleveland, OH (US)
- (**) Term: **15 Years**

(21) Appl. No.: **29/621,908**(22) Filed: **Oct. 12, 2017****Related U.S. Application Data**

- (63) Continuation of application No. 29/533,723, filed on Jul. 21, 2015, now Pat. No. Des. 805,377.
- (51) **LOC (13) Cl.** **05-05**
- (52) **U.S. Cl.** **USPC** **D5/32; D5/62**

(57)

CLAIM

The ornamental design for a sheet with camouflage pattern, as shown and described.

DESCRIPTION

The sole FIGURE is a plan view of a sheet with camouflage pattern showing our new design.

The dot-dash broken lines surrounding the FIGURE depict the boundaries of the claim and form no part thereof.

1 Claim, 1 Drawing Sheet(56)
